(57) **CLAIM**

I claim the ornamental design for a wall-mountable back scrubbing or massaging mat, as shown.

DESCRIPTION

FIG. 1 is a top perspective view of the wall-mountable back scrubbing or massaging mat, showing my new design;

FIG. 2 is a top plan view thereof;

FIG. 3 is a bottom plan view thereof; and,

FIG. 4 is a side elevation view thereof.

CERTIFICATE OF CORRECTION

PATENT NO. : D916,374 S
APPLICATION NO. : 29/684909
DATED : April 13, 2021
INVENTOR(S) : Dennis Elijah Jemison

Page 1 of 4

It is certified that error appears in the above-identified patent and that said Letters Patent is hereby corrected as shown below:

On the Title Page

The Title Page, showing the illustrative figures, should be deleted and substitute therefor the attached Title Page.

In the Drawings

Delete drawing sheets 1-2 and substitute therefor the drawing sheets, consisting of Figs. 1-4, as shown on the attached pages.

Signed and Sealed this
Twenty-second Day of February, 2022
